UNITED STATES PATENT OFFICE.

DAVID S. FOSTER, OF SYRACUSE, NEW YORK.

AEROPLANE.

937,587.

Specification of Letters Patent. Patented Oct. 19, 1909.

Application filed September 17, 1908. Serial No. 453,386.

To all whom it may concern:

Be it known that I, DAVID S. FOSTER, citizen of the United States, and resident of Syracuse, in the county of Onondaga in the State of New York, have invented new and useful Improvements in Aeroplanes, of which the following, taken in connection with the accompanying drawings, is a full, clear, and exact description.

10 This invention resides in certain novel improvements in aeroplane-construction designed more particularly to solve the problem of direct ascension.

The primary object of the present invention is to provide simple and efficient power-driven means capable of effecting the aforesaid result, with the view of dispensing with the expensive and inconvenient appliances ordinarily employed for causing aeroplanes 20 to take flight. It is well known to persons familiar with aeroplanes, that it is the common practice to provide complex and expensive apparatus combined with a wheeled-support upon which the aeroplane is mounted, said support being designed to be moved rapidly along the ground by hand or propelled by suitable power-driven means for the purpose of imparting to the aeroplane sufficient momentum to cause it to rise to 30 such an elevation as to clear obstacles incident to its being propelled. The described method is not only expensive and unreliable, but in some instances is not practical, for the reason that the use of the wheeled-support 35 obviously requires a very large area of ground which must be flat and smooth and at the same time free from obstructions, and from the fact that in many locations a proper ground space can not be had.

40 Another object of my invention is to produce an aeroplane which shall be simple and inexpensive in its construction, and to provide efficient and reliable co-operating lifting-means and propelling-means which shall 45 act reciprocally in such a manner as to render the aeroplane self-controlling to the extent that it will adjust itself under varying forces of the currents of air when in flight and thus maintain its equilibrium, and furthermore, the object is to provide a single 50 manually-operated device for independently and conveniently regulating the actions of the power-driven lifting and propelling-means, in combination with a simple and 55 convenient steering-apparatus whereby the aeroplane can be effectually controlled.

Other objects of the invention will be apparent from the peculiar construction and arrangement of the component parts of the aeroplane hereinafter fully described and 60 claimed and illustrated in the accompanying drawings.

Referring to said drawings Figure 1 is a rear view of the aeroplane embodying my improvements; Fig. 2 is a vertical sectional view taken on the dotted line —X—X— and showing the general arrangement of the power-driven lifting-wheel and propelling-wheel, and the mechanisms for regulating their actions, and also showing the 70 steering-apparatus; Fig. 3 is an enlarged detail side view illustrating more clearly the said mechanisms; Fig. 4 is a detail plan view of the two connected regulating-mechanisms; and, Fig. 5 is an enlarged vertical 75 sectional view taken on the dotted line —Y—Y—.

Like numerals of reference indicate like parts in the several views of the drawings.

As an essential element my improved 80 aeroplane embodies a dirigible body constructed preferably in the form of a bi-plane, indicated at —1—1— in Fig. 1. This bi-plane comprises a horizontal skeleton frame composed of light bars of any suitable form and material. In the present case the bi-plane consists of a rectangular box-like structure comprising longitudinal top and bottom bars —2—2—, vertical bars —3—3—, and transverse bars —4—4— 90 which may be united by means of bolts or rivets. The front and rear sides of the bi-plane are open and the top and bottom are closed by sheets of canvas or other material —5—5— suitably fastened to the said bars 95 —2—2—. Intermediate of its ends the bi-plane is left open at the top and bottom as shown in Fig. 1, whereat it is provided with a car —6— for the person or persons in charge. This car depends from the aforesaid frame and may be of any suitable construction, but preferably comprises long vertical bars —7—7— fastened to the frame-bars —2—2— and connected at their lower ends by horizontal bars —8—8— designed 105 to support a floor —9—.

The lifting means of the aeroplane consists essentially of a horizontally-rotatable wheel comprising a hub —10— having a set of pivotal blades —11—11—, said hub being 110 secured to the upper end of a vertical hollow shaft —12— journaled in suitable bear-

ings —13—13— mounted in the frame. This shaft is disposed intermediate the ends of the bi-plane and at the center of its width and extends from the car above the top of the bi-plane. To the lower end of said shaft is secured a bevel-gear —14— meshing with a like gear —15— secured to the forward end of the shaft —16— of a suitable motor —17— mounted in the car in any convenient manner. The blades —11—11— of said lifting-wheel have pivotal connections with the hub —10— to permit of their adjustment to obtain the desired pitch to regulate the action of the wheel as will be shortly referred to. The said lifting-wheel may be of any suitable or well known construction. The style of wheel shown is similar to that of a reversible propeller-wheel common to power-driven boats. However, it will be understood that in the present instance I do not contemplate reversing the action of the blades, but simply turn them to vary the pitch, it being obvious that the angle of pitch is never to exceed 45 degrees. The hub —10— is formed hollow as usual and is divided diametrically, the line of division being transverse in relation to the shaft —12— so as to provide a removable outer section, and at the line of division are provided the usual radially disposed openings —18—18— forming bearings for the stems —19—19— of the blades.

The stems of the blades are provided with the usual cranks or levers —20—20— to which are connected the outer end of a longitudinally shiftable rod —21— extending through the hollow shaft —12—. The opposite end of the rod is provided with a transverse pin —22— adapted to move in a longitudinal slot 23— in the shaft, and embracing said shaft is a sleeve —24— provided with an internal circumferential groove or channel —25— engaged by the pin —22—. By moving this sleeve upward and downward on the shaft the rod —21— is caused to actuate the cranks or levers —20—20— on the stems of the blades, whereby the latter are turned so as to set them at the desired pitch. The construction and arrangement of the described parts being common in boat-propellers, further illustration is unnecessary.

Any suitable and convenient manually-operated mechanism may be employed for actuating the sleeve —24— for the purpose stated. A very simple actuating device is shown and consists of a vertically swinging lever —26— pivoted to the frame as indicated at —27— and connected to the sleeve by means of a rod —28—.

The propeller-wheel comprises the usual hollow hub —29— and pivotal blades —30—30—. Said propeller-wheel is mounted on the horizontal shaft —31— connected to the shaft —16— of the motor. The con-

struction of the propeller-wheel is identically like that of the aforesaid lifting-wheel, and therefore it does not require further illustration or description, it being understood that the shaft —31— is hollow 70 to accommodate a longitudinally shiftable rod operative for changing the pitch of the blades. The rod is shifted by means of the sleeve —32— sliding upon the shaft —31—, the connection between said rod and sleeve 75 being the same as the connection between the aforesaid rod —21— and sleeve —24— employed for adjusting the lifting-wheel blades. The sleeve —32— is actuated by means of a longitudinally movable horizontal rod —33— disposed parallel with the shaft —31— and pivotally connected at one end to said sleeve as indicated at —34—, the opposite end of said rod being provided with a suitable handle —35—. In order that the 80 blade-adjusting mechanisms of the two wheels may be actuated by this handle —35—, I provide the rear end portion of the lever —26— with a longitudinal slot —36— through which passes a transverse 85 pin —37— securely fastened to the adjacent end portion of the rod —33—, to which pin I apply the said handle as clearly shown in Figs. 3 and 4 of the drawings. By connecting the lever —26— and rod —34— in 90 the manner described it is obvious that the person in charge is enabled by the single handle to independently and conveniently regulate the actions of the wheels. By thus regulating the actions of the wheels and 95 providing a suitable steering-apparatus, the aeroplane can be easily and conveniently controlled in its ascension and descension and in its propulsion.

The steering-apparatus may be of various 100 constructions and arranged in any manner practical for the requirements. The preferred form of steering-apparatus however, comprises a rectangular-shaped box —38— composed of a suitable frame covered on its 105 sides with canvas or other material and having its ends open. This box may be of any convenient size and it is supported at the front side of the frame of the bi-plane. To render this steering-box capable of directing the bi-plane in any desired course, it is 110 obviously necessary that it be permitted to be swung both vertically and laterally. Said box projects from the bi-plane and is disposed at the center of the length thereof and 115 it is preferably mounted on a bracket suitably secured to one of the frame-members. In the present instance the bracket is of substantially U-shape and comprises a horizontal bar —39— and a pair of vertical 120 arms —39— rigidly secured to or formed integral with the end portions of the bar, between which arms the said box is pivotally supported, as indicated at —40—, to allow it to swing vertically. This bracket 125

also comprises a vertical stem or shaft 41— depending from the bar 39— and mounted revolubly in a suitable bearing 42— secured to the frame of the bi-plane 5 whereby the bracket may be turned to swing the steering-box laterally.

The stem 41— protrudes some distance below the bearing 42— and is provided with a longitudinal slot 43— through 10 which passes a rod 44— disposed parallel with the steering-box and connected at its forward end to the corresponding end of the box, the rear end of said rod being provided with a suitable handle 45— for 15 operating it. The rod, when moved forwardly and rearwardly, causes the forward end of the steering-box to be raised and lowered. When the handle 45— is moved 20 sidewise the bracket is turned correspondingly, whereby the box is swung laterally. It is obvious that the turning of the bracket results from the engagement of the rod 44— with the slot in the stem 41—.

While the described device for operating 25 the steering-box is efficient, at the same time it will be understood that other means may be employed for the purpose.

The operation of the aeroplane is as follows: Assuming the same to be resting upon 30 the ground, the person in charge places the handle 35— in such position as to entirely relieve the blades of the lifting-wheel and propeller-wheel from pitch, and then starts the motor in the usual and well known manner. Upon starting the motor, the operator 35 moves the said handle 35— either up or down, according to the arrangement of parts, whereby the blades of the lifting-wheel are given a partial or full pitch, as 40 conditions may require, to cause the bi-plane to ascend. When the desired height has been reached, the operator moves the handle 35— whereby the rod 33— and sleeve 32— are caused to set the propeller-blades 45 at the required angle or pitch, and then raises or lowers the handle to actuate the lever 26— and thus shift the sleeve 24— on the vertical shaft 12—, whereby the pitch of the blades of the lifting-wheel is 50 decreased, which causes the bi-plane to travel forward, the direction of travel being dependent upon the adjustment of the afore-

said steering-box. If during the flight of 55 the bi-plane, it encounters strong winds tending to overturn the same, the operator moves the aforesaid handle 35— to give a certain amount of pitch to the lifting-blades, whereby the structure is caused to resist 60 the force of the wind and the equilibrium thereof preserved. It will be evident that, when the blades of a lifting-wheel are given a partial pitch the revolution of the wheel will sustain the bi-plane, 65 and if, when full pitch is given to said blades, a slight pitch is given to the blades of the propeller-wheel, the bi-plane will be driven forward and at the same time caused to rise. By the co-action of the two 70 wheels, it will be seen that they will act reciprocally, *i. e.* the increasing of the pitch of the blades of one wheel proportionately decreases the power of the other wheel. By providing the described convenient and 75 positive adjustment of the lifting-wheel and propeller-wheel, it is evident that the aeroplane can be easily controlled so as to descend to the desired place upon the ground.

What I claim is:—

The combination with an aeroplane, of a motor mounted thereon, a suitably supported vertical rotary shaft extending above the aeroplane, mechanism transmitting motion from the motor to the said shaft, a lifting-wheel mounted on the upper end of the said shaft, and having a set of pivotal blades, a horizontal shaft driven by the motor, a propeller-wheel secured to the horizontal shaft and having a set of pivotal blades, adjusting 85 mechanism connected to the blades of the two wheels for varying the pitch thereof to increase or decrease the power of the wheels, the two sets of blades being capable of independent adjustment whereby the increase 90 and decrease of the power of one wheel will effect a corresponding decrease and increase of power in the other wheel, and manually, operated means for controlling the said adjusting mechanism to either independently 95 or simultaneously change the pitch of the two sets of blades as set forth.

DAVID S. FOSTER.
